UNITED STATES PATENT OFFICE.

EDWARD R. DE LUIZ, OF DETROIT, MICHIGAN, ASSIGNOR TO KELVINATOR CORPORATION, OF DETROIT, MICHIGAN, A CORPORATION OF DELAWARE.

EXPANSION VALVE.

Application filed June 1, 1920. Serial No. 385,501.

To all whom it may concern:

Be it known that I, EDWARD R. DE LUIZ, a citizen of the United States, residing at Detroit, in the county of Wayne and State 5 of Michigan, have invented a certain new and useful Improvement in Expansion Valves, of which the following is a full, clear, and exact description, reference being had to the accompanying drawings.

10 This invention relates to refrigerating apparatus and has especial reference to the pressure reducing valve or expansion valve employed for admitting the refrigerant liquid into the expansion chamber at the necessary rate for efficient refrigeration. 15 The objects of the invention are the provision of a device of this character which shall be simple, efficient, noiseless, leakproof, readily assembled and easily adjusted; the 20 provision of a device of this character containing a straining or filtering cell which shall offer the maximum possible filtering area and be proof against clogging and also easily cleaned; while further objects and advantages of this invention will become apparent as the description proceeds.

In the drawings accompanying and forming a part of this application, I have shown certain embodiments of my invention although without intent to restrict myself to the particular physical forms therein delineated. In this drawing, Fig. 1 is a central sectional view through my preferred construction of valve; Fig. 2 represents a 35 front elevation of the device shown in Fig. 1; and Fig. 3 illustrates the device in operative position relatively to the expansion coil with which it is used.

I have shown my improved valve as employed in connection with the expansion coil and brine tank set forth in the Copeland et al. application, filed January 14, 1918, Ser. No. 211,753 and in the Copeland application filed October 24, 1919, Ser. No. 332,907, although without intending to restrict myself to such use excepting as specifically set forth in my claims. This coil comprises an initial part 1 into which refrigerant is first admitted and a terminal part 2 from which the spent refrigerant passes to the return pipe 3. The part 1 is preferably immersed in a brine tank 4 and the expansion valve is attached to the upturned end 5 of this part, fresh refrigerant under pressure being delivered to the valve by the pipe 6.

My improved valve comprises a hollow casing 10 having at its rearward end the screw threaded opening 11 and at its forward end the flaring circular web 12 terminated by the circular rim 13. The portions 10 and 12 are hollowed out to form a valve chamber and a diaphragm chamber respectively, such chambers being separated by a partition 14 formed with an axial opening 15. The lower part of the casing is 60 formed with two independent depending passageways 16 and 17, which communicate with the valve-chamber and diaphragm chamber, respectively. The passageway 17 leads to the pipe connection 18 to which the expansion coil is attached, and the side of the passageway 16 is formed with the pipe connection 19 to which the refrigerant pipe 6 is connected.

The passageway 16 is preferably enlarged 75 at a point between its ends to form a sediment chamber, and opens into the valve chamber through a tapered opening 20, while its outer end is closed by means of the screw plug 21. Located inside this sediment chamber is a filter cell, preferably comprising a pair of spaced heads 23-24 connected by an axial post 25 and by an external cylindrical screen 26 of very fine mesh. The head 23 is tapered so as to seat tightly in the opening 20 and is formed with perforations 27. The plug 21 carries a suitable spring 28 which presses against the opposite head and holds the cell in place. Any sediment is deposited on the exterior of the screen 90 and either falls to the bottom of the chamber or can be readily cleaned off by removing the cell.

To the rim 13 is bolted the companion rim 30 of a cover plate 31 whose center is formed with an internally threaded cylindrical barrel 32 coaxial with the aperture 15. Between the rims the flexible diaphragm 33 is hermetically clamped. The inner face of the plate 31 is formed with a shallow circular recess 34 loosely receiving the wear plate 35 whose center is provided with a boss 36 embraced by one end of the helical spring 37 whose opposite end rests against the adjustable plug 38 which is screwed inside the barrel 32. Outside of this plug I have shown the lock plug 39.

Mounted in the valve chamber is the valve member 42 having a stem 43 projecting through the aperture 15 and having a seat-

ing portion cooperating with said aperture. At its forward end this stem rests loosely against a wear plate 44 which in turn rests against the face of the diaphragm and is held against displacement by suitable notched fingers 45 which project from the partition 14. At its rearward end the valve is engaged by a helical spring 47 whose opposite end rests against the plug 48 which closes the opening 11. The springs 37 and 47 therefore act in opposite directions, one tending to close the valve and the other to open the same, while their relative effect is adjusted by moving the plug 38, which can be effected without securing access to the refrigerant side of the diaphragm and without danger of producing leakage.

Having thus described my invention, what I claim is:—

1. In a pressure reducing valve, a casing having therein an elongated valve chamber and a diaphragm chamber, a partition between said chambers and having an aperture therein, said casing also having a passageway leading downwardly from each of said chambers, the passageway which communicates with the diaphragm chamber constituting an outlet and the other passageway constituting a filtering chamber, removable closures for said valve chamber and filtering chamber, a filtering cell comprising a pair of spaced heads and a screen connecting them, one of said heads being apertured and seated in the orifice which establishes communication between said last mentioned chambers, means including the closure of said filtering chamber for holding said cell in place, the wall of said filtering chamber being formed with an inlet opening, a valve in said valve chamber adapted to close said first aperture, and having a stem projecting through that aperture, a spring for closing said valve, a diaphragm traversing said diaphragm chamber and adapted when deflected to displace said stem, a cover plate on the opposite side of said diaphragm from said casing, and an adjustable spring carried by said cover plate and tending to move said diaphragm against the tension of said first spring.

2. In a pressure regulating valve a casing having a valve chamber and a diaphragm chamber, a partition between said chambers and having an aperture therein, said aperture being located at the center of said diaphragm chamber, a plurality of fingers carried by said partition and having notches in their outer faces, a plate loosely located in said notches, a diaphragm traversing said chamber and passing close to said plate, a cover plate having a rim secured to the rim of said diaphragm chamber and clamping said diaphragm, the face of said plate which overlies said diaphragm having a circular cavity, a circular plate loosely received in

said cavity and pressing against said diaphragm, said cover plate having an internally threaded barrel in line with said aperture, an adjustable plug screwed in said barrel, a spring interposed between said plug and said last mentioned plate, a valve member in said valve chamber and having a stem projecting through said aperture into engagement with said first mentioned plate, and a spring in said valve chamber pressing said valve member towards said diaphragm.

3. In a pressure regulating valve, a casing having therein a horizontal valve chamber and a depending chamber communicating therewith through a narrowed orifice, a cover plate secured to the end of said casing and defining therewith a circular diaphragm chamber coaxial with said valve chamber, said casing having an inlet opening in the side of said second chamber and an outlet opening in the side of said diaphragm chamber and the ends of said inlet chamber and valve chamber being formed for the reception of closure devices, a filter cell located in said second chamber and having a pair of spaced heads surrounded by a screen, one of said heads being apertured and received tightly in said orifice, a diaphragm traversing said diaphragm chamber, a valve member in said valve chamber and having a stem projecting into said diaphragm chamber, and spring means cooperating with said diaphragm for operating said valve.

4. In a pressure regulating valve, a casing having a sediment chamber, a valve chamber, and a diaphragm chamber, partitions between said chambers, said valve chamber communicating with each of the other chambers through apertures in said partitions, a filter cell in said sediment chamber and located in the aperture which leads to the valve chamber, a valve member in the valve chamber and having a stem projecting through the aperture which leads to the diaphragm chamber and a diaphragm in said diaphragm chamber and operatively associated with said stem, the aperture which leads from said sediment chamber to said valve chamber being located in the upper part of said sediment chamber and said sediment chamber also having an inlet connection located at a point above its bottom.

5. In a pressure regulating valve, a casing having therein a horizontal valve chamber and a depending chamber communicating therewith through a narrowed orifice, a filter cell located in said second chamber and having a pair of spaced heads, surrounded by a screen, one of said heads being apertured and received tightly in said orifice, a post connecting said heads inside said screen, a removable closure for the end of said second chamber which is opposite said orifice, and a spring interposed between said closure and the adjacent end of said cell.

6. In a pressure regulating valve, for refrigerating apparatus, a casing having a valve chamber and a diaphragm chamber, a diaphragm located in said diaphragm chamber, a partition between said chambers and having an aperture therein, a valve member in said valve chamber having a seating portion adapted to close said aperture and a stem which extends into operative relation with said diaphragm, spring means in said valve chamber tending to close said valve, spring means upon the opposite side of the diaphragm tending to open said valve, means for supporting said casing with said valve stem in a substantial horizontal position, said casing having a depending pocket communicating with said valve chamber, a filtering cell in said pocket, an inlet pipe communicating with said pocket above the bottom thereof, and an outlet pipe communicating with the lowest point of said diaphragm chamber.
7. In refrigerating apparatus, in combination, an expansion coil, and a pressure regulating valve comprising a casing having a valve chamber and a diaphragm chamber, a diaphragm located in said diaphragm chamber, a partition between said chambers and having an aperture therein, a valve member in said valve chamber having a seating portion adapted to close said aperture and a stem which extends into operative relation with said diaphragm, spring means in said valve chamber tending to close said valve, spring means upon the opposite side
5. of said diaphragm tending to open said valve, means supporting said casing with said valve stem substantially horizontal, there being an outlet passage extending downwardly from the lowest point of said diaphragm chamber into said expansion coil, and an inlet passage way leading upwardly into said valve chamber.
8. In refrigerating apparatus, in combination, an expansion coil having a downwardly extending inlet connection, an expansion valve secured to said inlet connection and comprising a casing having therein a diaphragm chamber and a valve chamber and an apertured partition between said chambers, a diaphragm located in said diaphragm chamber, a valve member in said valve chamber having a seating portion adapted to close the aperture and a stem which extends into operative relation to said diaphragm, spring means tending to close said valve, spring means tending to move said diaphragm in a direction to open said valve, said valve stem being substantially horizontal and the connection to said expansion coil communicating with the lowest part of said diaphragm chamber, said casing also having a well located beneath and communicating with said valve chamber and an inlet connection communication with said well at a point above its bottom.
6. In testimony whereof, I hereunto affix my signature.
- EDWARD R. DE LUIZ.
